UNITED STATES PATENT OFFICE.

CLYDE D. HELM, OF FORT WORTH, TEXAS, ASSIGNOR TO PERFECTION ICE SCORING MACHINE COMPANY, OF WACO, TEXAS, A CORPORATION OF TEXAS.

FLUID-PRESSURE-OPERATED ICE-SCORING MACHINE.

Application filed September 13, 1927. Serial No. 219,206.

My invention relates to ice scoring machines and more particularly to certain improvements for making such machines automatic in action; and the object is to provide machines which are simple in construction and operation and which can be made and installed at relatively small expense. Another object is to provide pneumatic means for handling blocks of ice. The advantage is that the blocks of ice can be more easily and readily elevated and shifted. Other objects and advantages will be fully explained in the following description and the invention will be more particularly pointed out in the claims.

Reference is had to the accompanying drawings which form a part of this application.

Fig. 1 is a side elevation of the machine.

Fig. 2 is a front elevation of the same.

Fig. 3 is a diagrammatic view of the pneumatic control.

Fig. 4 is a detail view of the gearing.

Fig. 5 is a vertical section of the two valve casings and the valves.

Fig. 6 is a vertical section of one of the valves and the casing therefor.

Similar characters of reference are used to indicate the same views throughout the several parts.

The machine is provided with a frame, preferably of angle or channel bars. Bars 1 form a base to which are attached uprights 2 and 3. Longitudinal bars 4 and 5 are attached to the uprights 2 and 3 respectively. The machine frame is further braced by the cross bars 6 which are attached to uprights 2 and 3.

Shafts 7 are journaled in bearings 8 which are attached to the uprights 2 and 3. Saws 9 for scoring the ice blocks are rigid with shafts 7. The machine has an extended frame provided with uprights 19 and longitudinal beams 11 and cross beams 12 for bracing purposes. Vertical shafts 20 are journaled in bearings 13 which are attached to the beams 1 and 11. The shafts 20 are driven by bevel gear wheels 14 and saws 15 are rigid with and driven by the shafts 20 for scoring the blocks of ice horizontally. The shaft 7 on the right hand side of the machine drives a gear wheel 14 by means of a gear wheel 21 which is rigid with shaft 7 and in this manner the shaft 20 on the right hand side of the machine is driven and so

drives the horizontally disposed saw 15 on that side of the machine. The wheel 21 meshes with wheel 22' and drives a shaft 22. This shaft 22 drives a bevel gear wheel 23 which drives a bevel gear wheel 24 which is rigid with and drives a shaft 7 on the left hand side of the machine. The gear wheel 23 also drives a gear wheel 14 which is rigid with and drives a shaft 20 and saw 15 on the left hand side of the machine. All the gearing is driven from a motor 25 which drives a shaft 26. A sprocket wheel 27 is rigid with shaft 26 and drives a chain 28 which drives a sprocket wheel 29 which is rigid with shaft 7 on the right side of the machine.

The motor 25 drives the pump 30 by means of a sprocket wheel 31 which drives a sprocket chain 32 and the chain 32 drives a sprocket wheel 33 which is rigid with the pump shaft. The pump 30 supplies the compressed air, or other fluid.

The machine is provided with a platform 34 for elevating and lowering the ice. The ice is elevated past the saws 9 which score the blocks vertically. The elevator 34 may be elevated by pneumatic or hydraulic means. Cylinders 35 and 36 are suspended from beams 4 and 5 by means of bolt holes 37 and bolts 38. The cylinders are provided with pistons and piston rods 39. The piston rods 39 are connected to the platform 34 by means of relatively wide brackets or connections 40.

Means are provided for moving the pistons in the cylinders 35 and 36. A pipe 41 leads from the pump 30 to a valve 42. The valve 42 has a disk 42' rigid with the stem thereof and the disk 42' has a notch 51 in its periphery. The valve 42 is connected to the lower ends of the cylinders 35 and 36 by means of a flexible conduit 43 which is connected to a nipple 44 on the casing of valve 42 and connected to a T-pipe 45 which is connected to pipes 46 which are connected to the lower ends of the cylinders 35 and 36. The valve 42 is provided with a handle or crank 47. A pull rod 48 operates the valve 42 by means of handle 47. A dog 49 is pivotally mounted on a bearing bar 50 which is rigidly attached to the beam 4. The dog 49 has a point which drops into a notch or recess 51 in the disk 42' of valve 42 for locking said valve temporarily against turning. To let compressed fluid pass through the valve 42, pull on the rod 48. This will

open the valve so that the fluid will pass through and on into the cylinders 35 and 36 to raise the pistons in the cylinders. The pistons raise the platform 34 and the block of ice. The saws 9 score the sides of the block of ice as it goes upwardly. The dog 49 holds the valve 42 open until the dog is raised out of the notch 51. Provision is made for raising the dog 49 automatically. A rod 52 is pivotally connected to the dog 49 and provided with a button on the lower end. When the block of ice reaches just about its upper limit of travel, the platform 34 will raise the trip rod 52 and so release the dog 49 from the valve 42. A spring 53 attached to the handle 47 and to the bearing bar 50 for bringing the valve 42 to closed position. At the same time the valve is closed against the passage of compressed fluid, the valve 42 is opened to the exhaust pipe 54 so that the compressed fluid will pass from the cylinders back through the pipe 43 to the exhaust pipe 54 and its branch pipe 55. The block of ice will then force the pistons of cylinders 35 and 36 down.

After the valve 42 is closed against the passage of fluid pressure to cylinders 35 and 36 and the exhaust is opened through pipe 54, the block of ice goes down. At the same time operations are commenced to move the block of ice horizontally towards the rear of the machine. The block of ice is moved by fluid pressure. When the fluid pressure is cut-off from the cylinders 35 and 36 by the valve 42, the pressure can then be diverted through a valve 56. A cylinder 57 is provided for moving the ice out of the machine. A flexible pipe 58 is connected to the valve 56 and to the cylinder 57 for letting fluid in the cylinder to move the piston therein. The valve 56 has a notch or recess 59 in a disk 56' which is rigid with the stem of the valve 56. A lever 60 is made temporarily rigid with the valve 56 for turning the valve. A rod 61 is pivotally connected to the lever 60 and slidably connected to a bracket 62 which is attached to the platform 34. A lug 63 is rigid with the rod 61. The lever 60 is normally loosely mounted on the stem of valve 56. The lever 60 actuates a dog 64 which is pivotally mounted thereon. When the block of ice reaches its upper limit or approximately its upper limit, the bracket 62 will lift the rod 61 by forcing the lug 63 upwardly. The lever 60 will be moved and the lever will bring the dog 64 into the notch 59 of disk 56'. This will lock the lever 60 and the stem of valve 56 rigidly together. When the block of ice with the platform 34 moves downwardly, the bracket 62 will slide on the rod 61 until the bracket 62 engages the lug 65 which was elevated to the dotted outline position when the bracket lifted lug 63. The bracket will then pull down on the rod 61 and the rod 61

will actuate the lever 60 and the lever will then actuate the valve 56 by reason of the dog 64 engaging the notch 59 in the disk 56' and so turn the valve and open the same for the passage of fluid pressure to the cylinder 57. By this time the block of ice has been lowered and ready to be moved out of the machine. The piston in cylinder 57 is connected to an arm 66 by a rod 67. When the piston in cylinder 57 is moved by the fluid pressure, the arm 66 will move the end 66' which will score the ice horizontally. Provision is made for closing the valve 56 when the arm 66 reaches its limit and has pushed the ice out of the machine. A rod 68 is pivotally connected to a lever 69 which is fulcrumed on the machine. The rod 68 carries a lug 70 rigid therewith. The arm 66 is loosely connected to and slidably off the rod 68 and is adapted to engage the lug 70. The short arm 71 of lever 69 is adapted to engage and move a curved arm 72 of the dog 64. Just as the ice block is moved out of the machine the upper end 73 of arm 66 will pull

on the rod 68 by engaging the lug 70. The rod 68 will actuate the lever 69 to move the dog 64 by pushing on the curved arm 72. This will release the dog 64 from the disk 56' of valve 56 and the valve 56 will be brought back to closed position by a spring 75. At the same time the valve 56 is closed to the passage of fluid pressure, it is brought to exhaust position so that the pressure in the cylinder 57 will escape and let the piston go back to normal position.

This invention is intended to apply not only to such machines as are herein described, but also is intended to cover fluid pressure means as used to move ice blocks in contact with scoring means in any type of machine or device for scoring manufactured ice.

What I claim, is:—

1. An ice scoring machine having an upright frame, horizontal shafts journaled in said frame and saws rigid with said shafts, fluid pressure for moving a block of ice vertically past saws for scoring the ice vertically, means for automatically cutting off the fluid pressure to permit the block of ice to descend vertically past said saws, and means for automatically discharging the block of ice from the machine.

2. An ice scoring machine having an upright frame, horizontal shafts journaled in said frame and saws rigid with said shafts, a platform for carrying a block of ice, fluid pressure means for moving said platform vertically and for moving the block of ice against and past said saws for scoring the

- ice vertically, and means actuated by said platform for automatically releasing the fluid pressure means for permitting the platform to descend.
3. An ice scoring machine having an upright frame, horizontal shafts journaled in said frame and saws rigid with said shafts, a platform for carrying blocks of ice past said saws, fluid pressure cylinders provided with pistons and piston rods operatively connected to said platform for moving the same, a valve having an intake port and an exhaust port operatively connected to said cylinders, manually operated means for opening said intake port, and means set in the path of said platform and actuated by the movement of the platform for automatically closing said intake port and opening said exhaust port to permit said platform to descend.
4. An ice scoring machine having a frame, shafts journaled in said frame and saws rigid with said shafts, a platform for carrying blocks of ice past said saws, fluid pressure cylinders provided with pistons and piston rods operatively connected to said platform for moving the same, a valve having an intake port for supplying fluid pressure to said cylinders and an exhaust port operatively connected to said cylinders to permit escape of fluid pressure from said cylinders, manually operated means for opening said intake port, means for holding said intake port open, means actuated by the movement of said platform for releasing said holding means, and means for automatically closing said intake valve and opening said exhaust valve to permit said platform to return to normal position.
5. An ice scoring machine having an upright frame, horizontal shafts journaled in said frame, saws rigid with said shafts, a platform for carrying blocks of ice, fluid pressure cylinders mounted on said frame and provided with a valve having an intake port and an exhaust port and provided with pistons and piston rods all operatively connected with said platform for moving said platform vertically, means for supplying fluid pressure to said cylinders through said intake port, means operatively connected to said valve and said platform whereby the movement of said platform actuates said valve automatically to stop the supply of fluid pressure to said cylinders, and to open the exhaust, and means for driving said saws.
6. An ice scoring machine having an upright frame, horizontal shafts journaled in said frame, saws rigid with said shafts, a platform for carrying blocks of ice past said saws, fluid pressure cylinders mounted on said frame and provided with a valve having an intake port and an exhaust port and said cylinders provided with pistons and piston rods, all operatively connected with said platform for moving the same, means for supplying fluid pressure through said intake port to said cylinders for actuating said pistons and piston rods, manually operated means for opening said intake port, means for temporarily locking said valve against movement, means set in the path of said platform and actuated by the movement thereof for releasing the locking means, and means for automatically closing said intake port and opening said exhaust port to permit said platform to return to normal position.
7. An ice scoring machine having an upright frame, horizontal shafts journaled in said frame, saws rigid with said shafts, fluid pressure means for moving a block of ice past said saws vertically and in contact with said saws for scoring the ice vertically, means for automatically cutting off the fluid pressure to permit the block of ice to descend vertically past said saws, and fluid pressure actuated means for discharging a block of ice from the machine.
8. An ice scoring machine having an upright frame and a horizontal extension, horizontal shafts journaled in said upright frame and vertical shafts journaled in said extension, saws rigid with said shafts, fluid pressure actuated platform for moving a block of ice in said upright frame in contact with and past said saws, means actuated by the movement of said platform for releasing the fluid pressure, and fluid pressure means for automatically moving the block of ice in contact with and past the saws in said extension and discharging the block of ice from the machine.
9. An ice scoring machine having an upright frame and a horizontal extension, saws provided with shafts journaled in said upright frame for scoring ice blocks vertically and saws provided with shafts journaled in said extension for scoring ice blocks horizontally, a platform for carrying blocks of ice, fluid pressure means for moving said platform vertically in said upright frame past said saws, means for automatically releasing the fluid pressure to permit said platform to descend, and fluid pressure actuated means automatically started by said platform for moving said block of ice past the saws in said extension and out of the machine.
10. An ice scoring machine having an upright frame and a horizontal extension, saws provided with shafts journaled in said upright frame for scoring blocks of ice vertically and saws provided with shafts journaled in said extension for scoring ice blocks horizontally, a platform for carrying blocks of ice, fluid pressure means for elevating said platform and means actuated by said platform for releasing the fluid pressure to permit said platform to descend, fluid pres-

sure means for moving said blocks of ice through said extension for scoring the ice blocks and discharging the same from the machine, and means actuated by said platform automatically for starting the last mentioned fluid pressure means.

11. In an ice scoring machine, scoring means consisting of rotatable saws and shafts therefor, a fluid pressure actuated platform for moving blocks of ice in contact with and past said saws, and a means actuated by the movement of said platform for releasing fluid pressure to permit platform to return to normal position.

12. In an ice scoring machine provided with scoring means, a fluid pressure actuated platform for moving blocks of ice in contact with and past said scoring means, means for producing fluid pressure to actuate the platform during the scoring operation, and means set in the path of said platform and actuated by the movement thereof for releasing the fluid pressure.

13. In an ice scoring machine provided with scoring means, a fluid pressure actuated platform for moving blocks of ice in contact with said scoring means, and a valve having an intake port for supplying fluid pressure and an exhaust port, and means set in the path of said platform and actuated by the movement of the platform for moving the valve to close said intake port and open said exhaust port to permit said platform to return to normal position.

14. In an ice scoring device provided with scoring means, fluid pressure actuated means for moving blocks of ice in contact with said scoring means, means for supplying fluid pressure to the moving means, and means actuated by the movement of said fluid pres-

sure actuated means for releasing the fluid pressure to permit the said last mentioned means to return to normal position.

15. An ice scoring machine having driven scoring means, fluid pressure means and a platform actuated thereby for moving blocks of ice past and in contact with said scoring means, means actuated by said platform for automatically releasing the fluid pressure means therefrom to permit said platform to return to normal position, and fluid pressure actuated means for automatically discharging blocks of ice from the machine.

16. An ice scoring machine having scoring means consisting of rotatable saws and a shaft therefor, a fluid pressure actuated platform for moving ice blocks in contact with said scoring means, and means actuated by said platform to arrest the movement of the platform and permit the same to return to its normal position.

17. An ice scoring machine having scoring means for scoring ice vertically and horizontally consisting of rotatable saws, horizontal and vertical shafts for said saws, a fluid pressure actuated platform for moving blocks of ice in contact with saws on said horizontal shaft, means actuated by said platform for arresting the vertical movement of the platform and to permit the same to return to its normal position, and fluid pressure actuated means operated by the movement of said platform to discharge blocks of ice from the machine and simultaneously to move the blocks of ice against the saws on said vertical shaft for scoring the ice blocks horizontally.

In testimony whereof, I set my hand, this 12th day of March, 1927.

CLYDE D. HELM.
